UNITED STATES PATENT OFFICE.

CHARLES W. FISCHER, OF SPARKS, NEBRASKA.

SHOE-LACE BUCKLE OR LOCK.

1,040,918.

Specification of Letters Patent.

Patented Oct. 8, 1912.

Application filed November 2, 1911. Serial No. 658,212.

To all whom it may concern:

Be it known that I, CHARLES W. FISCHER, a citizen of the United States, residing at Sparks, in the county of Cherry and State 5 of Nebraska, have invented certain new and useful Improvements in Shoe-Lace Buckles or Locks, of which the following is a specification.

This invention has for its primary object 10 the provision of a device independent of the shoe to which it may be applied, which is adapted to secure the bow of a shoe lace and at the same time form an ornamental appearance of a buckle.

15 A further object of the invention is to provide a fastener which in its use will prevent the usual entanglement of the ends of the lace resulting generally in a double knot being tied when it is desired to loosen 20 the bow.

With the above and other objects in view, this invention consists of the construction, combination, and arrangement of parts, all 25 as hereinafter more fully described, claimed and illustrated in the accompanying drawings, wherein:—

Figure 1 is a partial view of a laced shoe having my invention applied thereto; Fig. 2 is a side elevation of the fastener; Fig. 3 30 is a sectional view taken about on the line 3—3 of Fig. 1; Fig. 4 is a detail view of the base plate; Fig. 5 is a perspective view of the clamping member; and, Fig. 6 is a perspective view of the locking tongue.

35 Throughout the following detail description, on the several figures of the drawings, similar parts are referred to by like reference characters.

Referring to the drawings, the device 40 comprises a base plate 1, slightly curved longitudinally to conform to the curvature of a shoe to which it may be applied, said plate having at its lower portion a slot 2 extending to and being somewhat enlarged 45 at the central portion of the plate. Stamped from the body portion of the plate 1 are the spaced ears 3 in which is pivotally mounted a U-shaped clamping member 4, said pivot being located at a suitable place between the 50 extremities of said clamping member, as indicated at 3'. Pivoted at one end of said clamping member 4 is a locking tongue 5 having at its upper extremity a cam 6 which

is adapted to bear against the base plate 1 when it is desired to lock the fastener in its 55 operative position on a shoe lace.

While I have illustrated a desirable ornamental form of base plate, I do not desire to be limited to said shape, any fanciful design for which may be used and still perform the functions desired.

The operation of the fastener may be readily understood by reference to the drawings. The fastener is adapted to be used in connection with either high or low shoes and 65 is first secured to the shoe lace by passing the slot 2 in the base plate 1 over the ends of said lace beneath the bow 7. The loop ends of the bow are then drawn up through the opening 8 in the clamping member 4 70 and said clamping member will then bear against the free ends of the shoe lace and the loops of the bow will rest against the upper side of the clamping member 4. The locking tongue 5 is then pressed downwardly against the bow knot, said downward movement bringing the cam 6 into engagement with the base plate 1 and raising the upper end of the clamping member 4, causing simultaneous clamping action of the 80 clamping member and locking tongue on the bow of the shoe lace. When it is desired to remove the fastener, it is only necessary to raise the locking tongue 5 which will release the cam from engagement with the 85 base plate 1 and permit the fastener to be readily released from engagement with the bow of the lace. As will be understood, the locking tongue 5 when in operative position or engagement with the bow is adapted to 90 be received in the opening of the clamping member, thus affording a more firm clamping action of the lace. As a further means of positively preventing the free ends of the lace from becoming entangled in the bow, 95 said free ends may be passed through openings 9 in the base plate at opposite sides thereof.

Having thus described my invention, what I claim as new is as follows:—

A fastener for shoe laces comprising a base plate having a slot in the bottom portion thereof and open at one end to position the fastener on the lace, a U-shaped clamping member pivoted between its ends on said base plate and comprising spaced side mem- 105

bers providing a free opening therebetween through which the bow ends may be inserted, the closed end of said member extending across the open end of the slot aforesaid, a 5 locking tongue pivotally mounted at the open end of the U-shaped clamping member and movable to a position between and in substantially the same plane as the sides of

the U-shaped clamping member to positively engage the lace bow at this point. 10

In testimony whereof I affix my signature in presence of two witnesses.

CHARLES W. FISCHER.
